UNITED STATES PATENT OFFICE.

ROBERT E. BOYLE, OF NORRISTOWN, PENNSYLVANIA.

DESIGN FOR A GAME OR PUZZLE BOARD.

SPECIFICATION forming part of Design No. 33,564, dated November 13, 1900.

Application filed July 19, 1900. Serial No. 24,228. Term of patent 3½ years.

To all whom it may concern:

Be it known that I, ROBERT E. BOYLE, a citizen of the United States, residing at Norristown, in the county of Montgomery and State of Pennsylvania, have invented and produced a new and original Design for a Game or Puzzle Board, of which the following is a specification, reference being had to the accompanying drawing, forming part thereof.

10 The accompanying drawing is a perspective view of my new and original design for a game or puzzle board.

15 *a* represents a rectangular body or frame having flat bottom *b*, marginal sides or walls *c*, and end walls *d*.

20 *e* are webs or partitions disposed centrally of the end walls *d* and perpendicularly in respect to the base. The outer edges of the webs are inclined, as at *f*.

sign is the game or puzzle board illustrated in the accompanying drawing, which is shown as consisting of a shallow oblong box or frame having a center board or base of greatly-increased area longitudinally and extremely 25 narrow in respect to its length and having a vertical web or partition at each extremity disposed centrally thereof, said partitions being sloped or inclined at their outer edges and each forming two compartments which 30 are greater in length than width.

Having thus described my invention, I claim—

The design for a game or puzzle board, substantially as herein shown and described. 35

ROBERT E. BOYLE.
